BURNER STARTING DEVICE AND WICK
THEREFOR

Rallston M. Sherman, Glastonbury, Conn., assignor to The Silent Glow Oil Burner Corporation, Hartford, Conn., a corporation of Connecticut

Application January 6, 1934, Serial No. 705,549

13 Claims. (CL 158—90)

This invention relates to burners employing liquid fuel (for descriptive purposes herein referred to as oil) and more particularly, though not exclusively, those in which a wick is employed for 5 starting or other purposes.

The invention is herein illustrated in connection with a burner of the combustion tube type in which an oil-saturated fire-resisting wick is lighted and used to preliminarily heat the burner, 10 after which the burner becomes self-vaporizing and the wick ordinarily ceases further to function.

In starting burners of this type the initial lighting of the wick is a troublesome and awkward 15 operation usually requiring the insertion of a lighted taper between the combustion tubes. It is also uncertain, often requiring repeated attempts before the wick is lighted, and usually results in a localized, slowly spreading flame, with an uneven combustion persisting for some length 20 of time.

One object, among others, of the present invention is to provide electrical means for lighting the wick of an oil burner comprising a resistance heating element preferably so disposed that when 25 current is caused to pass through the resistance element, the oil throughout a substantial length of the wick is quickly vaporized and ignited, with a resulting evenly distributed flame throughout 30 the entire extent of the wick.

Another object is to accelerate the full fire 35 operation of a combustion tube burner after the wick has been lighted.

Another object is to provide means for automatically cutting off the source of electric current when the proper stage has been reached in 40 the operation of the burner.

These and other objects of the invention will be best understood by reference to the following 45 description when taken in connection with the accompanying illustration of one specific embodiment thereof, while its scope will be more particularly pointed out in the appended claims.

In the drawings:

45 Fig. 1 is a plan view of a burner employing one form of the invention, the parts above the base and portions of the wicks being broken away;

Fig. 2 is a central sectional elevation of the 50 same burner taken on the line 2—2 of Fig. 1, intermediate portions of the combustion tubes being broken out;

Fig. 3 is an enlarged sectional elevation showing the two opposite ends of the outer one of the 55 two wicks with their electrical connections to the

terminals carried in but insulated from the burner base;

Fig. 4 is a plan in partial section taken on the line 4—4 of Fig. 3;

Fig. 5 is a sectional elevation on the line 5—5 5 of Fig. 3;

Fig. 6 is a side elevation of a portion of a wick having the resistance heating element in a different relationship from that shown in Figs. 1 to 5;

Fig. 7 is a sectional elevation taken through 10 the wick shown in Fig. 6; and

Fig. 8 is a plan view, Fig. 9 a side elevation, and Fig. 10 a sectional elevation showing a portion of a wick having the resistance heating element in 15 a still different relationship; while Fig. 11 is a fragmentary detail in section to a greatly enlarged scale showing a preferred form of fuel groove.

Referring to the drawings and first describing the specific form of burner in connection 20 with which one form of the invention is herein shown, the burner (Figs. 1 and 2) is provided with a base 11 in the form of a casting having an outer generally annular portion and an inner concentric annular portion spaced from but connected one to the other by a series of webs 13 and providing an annular air admission opening 15 between the two annular portions of the base interrupted only by the webs 13.

The inner annular portion is provided with a 25 central air admission opening 17 surrounded by an upstanding ring-like flange 19, the outer edge of the inner portion also having an upstanding ring-like flange 21 spaced from but concentric with the flange 19. The flanges 19 and 21 together with the connecting bottom wall of the base casting form a relatively wide annular compartment or channel 23 on the bottom of which is a raised wall or rib 25 extending around said channel but interrupted at intervals. Oil is 30 adapted to be delivered to the channel 23 by a pipe connection 27 opening into the bottom wall of the channel through the oil inlet opening 29, the latter being disposed between the rib 25 and the flange 19.

The outer annular portion of the base casting 35 presents an outer fuel compartment in the form of a channel 31 formed between the upright spaced flanges 33 and 35, the outer channel being of lesser radial width than the channel 23. 40 The outer channel 31 is connected to the inner fuel channel 23 by means of supply ducts 37 formed in the webs 13 so that a free circulation of liquid or vaporized oil takes place through both fuel channels. The top of the wide chan- 45

nel 23 is partly covered and closed by a removable annular cover plate 39 formed preferably of thin sheet metal, such as chromium steel, the inside edge of the plate having a down-turned flange to seat upon and within the upper base flange 19 with a preferably close fit. The walls of the cover plate extend outwardly and herein also downwardly but are spaced vertically from the bottom of the channel 23 5 and the raised rib 25 to provide an annular space through which vaporized oil may pass directly into the space between the flange 21 and the edge of the cover plate 39.

The edge of the cover plate has an out-turned 15 lip on which there is supported a perforated sheet metal cylinder 41 constituting the inner one of a pair of combustion tubes. A similar but larger concentric cylinder 43 is removably seated on the outer shouldered edges of the 20 flange 21 so that there is provided between the two cylinders an elongated combustion chamber 45 aligned with and constituting an extension of the outer uncovered edge of the wider channel 23. Two concentrically spaced perforated sheet metal cylinders 47 and 49 are likewise removably seated on the inner and outer shoulders, respectively, of the flanges 33 and 35, 25 providing between them a combustion chamber 51 having a relation to the outer fuel channel 31 similar to that of the combustion chamber 45 to the outer portion of the channel 23.

A removable annular top plate 53 is provided with its edges resting on the tops of the sheet metal cylinders 43 and 47 to close the top of the 35 annular air space therebetween, and a disc-shaped closure 55 with its edges resting on the upper edges of the cylinder 41 is similarly provided to close the top of the central air chamber, leaving, however, annular openings in the 40 tops of the two combustion chambers 45 and 51 for the escape of the products of combustion.

A burner of this type is commonly started by igniting an oil saturated wick usually comprising a fabricated strip of asbestos, the strip being 45 cut so as to rest in the fuel compartment or channel with its upper edge entered into the bottom of the overhead combustion chamber. In the illustrated device two such wicks 57 and 59 are shown, the first located in the outer fuel 50 channel and the other in the inner fuel channel. The inner wick 59 may have the portions coinciding with the ports 37 cut away to leave such ports unobstructed.

When the burner is to be started, oil is admitted through the inlet port 28 and enters the wide channel, flowing thereover within the raised rib 25, through the openings therein to the outer portion of the channel, and through the ducts 37 into the outer fuel channel 31, penetrating the bottom edges of both wicks and saturating the bodies thereof. The wicks being then lighted, the burner begins to heat, and when the required vaporizing temperature is reached the liquid oil becomes vaporized on entering the channel 23 beneath the cover plate 39, the covered portion of said channel constituting a vaporizing space. Combustion is then carried on to an increasing degree independently of the wick, and finally completely through 65 the oil vapor passing from the vaporizing chamber beneath the edge of the cover plate into the inner combustion chamber and into the outer combustion chamber through the ducts 37, and the wicks ceasing to function when the burner 70 operates under full fire.

To ignite the wick at any time after it has been saturated with oil, there is provided in the illustrated form of the invention a resistance heating element or resistor, herein carried by and incorporated in the wick itself. This is in the form of a conductor 61 threaded lengthwise 5 of the wick. While various relationships of the resistance element to the wick may be employed, two other examples of which are hereinafter given, in the form shown in Figs. 1 to 5 the conductor 10 is threaded through the material of the wick and spirally over the upper edge thereof. This places the resistance heating element in such a relationship and close proximity to the wick and edge thereof that when included in an electric circuit 15 it provides a continuous conducting path in which the heating current is localized at or near the edge of the wick and is capable of being brought to a sufficient heat to vaporize the oil in the saturated wick throughout substantially the entire 20 length thereof and to ignite the oil vapor with substantial uniformity throughout the entire extent of the annular space in which the wick is positioned, thereby providing a starting flame of 25 substantially uniform volume. Combined with the resistance heating elements are terminals positioned in but insulated from the base to which the ends of the conductor may be electrically connected and through which electric heating 30 current may be supplied at will.

In the illustrative embodiment of the invention each of the two wicks carries a resistance heating element, but, if desired, one wick only may be associated with the resistance heating element and the ignition of that wick may be relied on to 35 ignite the remaining wick or wicks.

In the illustrated embodiment of the invention, the wicks, resistance heating elements and connections and terminals therefor are substantially the same in construction and arrangement in the 40 case of both the outer and inner wicks 57 and 59, except as hereinafter mentioned, and specific description thereof will be confined to the outer wick 57.

In the present instance the wick is somewhat 45 thicker and heavier than usual in order to provide a self-sustaining form and body for the asbestos strip without the aid of the usual metallic reinforcements. If metallic reinforcements are employed, they should be so located, or such provision should be made, that they will not interfere with the heating function of the conductor 61. Asbestos being a non-conducting material, in the illustrated form of the invention, where the conductor is spirally threaded through the 50 asbestos in the manner indicated, the heating current is confined to the conductor and localized 55 at or near the edge of the wick.

Referring to Figs. 3, 4, and 5, the opposite ends of the wick as it lies in the groove 31 are separated by a space in which there is provided a pair of binding posts 63, 63 mounted in but insulated from a raised lug 65 formed in the base and filling the groove 31. Beneath the top of each binding post and electrically connected thereto, but insulated from the base, is a clip 67 of conductive metal and of L-shaped cross section through which, by means hereinafter described, connection is made from one binding post to one end of the resistance heating element 61 and through 60 the other binding post to the opposite end of said element.

Each binding post is connected to a conductor 69, which conductors are included in an electric circuit, diagrammatically represented at 71 in 75

Fig. 3, the circuit including a source of current 73 and a switch 75, so that when the switch is closed heating current is passed through the resistance heating element 61. In practice connections may be made to the usual house lighting circuit and the voltage stepped down by a suitable transformer.

The conductors for the resistance heating elements may be connected either serially or in multiple in the same circuit 71, or may be connected to separate sources of current as desired.

Combined with the electrical igniting device there is also provided means for effecting the automatic cut-out of the electric circuit after the lapse of an adequate interval and herein when the wick is fully ignited and the burner is in operation. Such automatic cut-out may be provided by various means including those operating on other than a thermostatic principle, but in the illustrative example there is provided for this purpose a thermal responsive device comprising a connection 77 of bimetallic thermostatic metal, such that, when the burner is cold and prior to the lighting of the wick, electrical connection is maintained, but, after the burner has attained a given stage of operation, the igniting current is cut off. The automatic cut-out device may be positioned in any suitable part of the burner. The heat generated soon after the burner becomes lighted will be sufficient to actuate a thermal responsive device having easily obtainable qualities of response if such device is located contiguous to any part of the base, the combustion tubes, or any other of the burner parts illustrated. In the illustrative example, however, the bimetallic connection 77 is positioned immediately above the groove 31 at the bottom of the chamber 51 and connected between the binding posts 63 and the end of the resistance heating element 61, its relationship being such that, after the wick has been lighted, the connection of the resistance heating element is automatically broken.

In the present instance a similar connection 77 is provided for each of the two binding posts 63, description being made of one only. If desired, however, a single make and break device only might be used at one end of the resistance heating element and a permanent connection be employed between the opposite end thereof and the remaining binding post. Or, in the case of two or more wicks, the resistance heating element for a plurality of wicks may be connected in series or in parallel and a single thermal responsive device employed to cut off the current from the resistance heating element of all said wicks.

Referring again to Figs. 3 to 5, inclusive, the bimetallic connection 77, as illustrated, is of curved or U-shaped form and has one leg thereof abutting against the edge of the wick and electrically connected to the end of the conductor 61. In that position it is held by the metallic sheath 79 of U-shaped cross section, which sheath overlies the vertical edge of the wick and is secured thereto by a pair of pins 81 passing through the sheath and the wick, so that the wick 57, conductor 61, connection 77 and sheath 79 are permanently bound and secured together. The pins 81, while extending through the wick and sheath, protrude outwardly slightly beyond the latter. The leg of the connection 77 is insulated from the sheath by an insulating lining 83. The opposite protruding ends of the pins 81 fit and may be inserted into the tops of the vertical grooves or

slots 85 formed in the flanged walls 33 and 35 of the base, thereby holding the end of the wick and likewise the bi-metallic connection 77 in fixed relationship to the binding posts 63 and the connecting clip 67.

The connection 77 curves upwardly and outwardly from the wick edge and thence downwardly, the downwardly curved leg thereof, when the burner is cold, pressing in close electrical contact against the upstanding part of the L-shaped clip 67. The shape of the connection 77, however, is such that it has a substantial opening movement when subjected to a high temperature (indicated by dotted lines in Fig. 3), so that, after the wick is lighted and the burner heats up, the resulting combustion in the bottom of the combustion chamber in and about the bimetallic connection 77 causes the latter to expand and open, breaking the contact between the depending leg thereof and the clip 67 and opening the circuit of which the conductor 61 forms a part. The thermostatic connection 77 is located in the zone of combustion and above the level of the wick. Its cross-sectional area and resistance are preferably such that it undergoes no such substantial expansion as to break the circuit during the passage of the heating current and before the wick has become ignited, but expands sufficiently to open the circuit only under the influence of combustion resulting from the ignition of the wick.

In installing the wick in the burner, it is seated in a groove and the ends of the wick, each with its bimetallic connection 77, are fixed in position by slipping the pins 81 into the vertical grooves 85, giving the connection 77 a definite position with relation to the binding posts 63. The clip 67 has a slightly elongated opening where the binding post passes through it, so that if any adjustment of the clip is required to secure good electrical contact between the clip and the connection 77 the binding post may be loosened and the clip adjusted to its desired relationship.

The provision for the inner wick 59 is substantially the same as that described in connection with the outer wick 57 except that the pin 81 protrudes only on the outer wall of the sheath and the bottom of the inner face of the sheath bears against the side of the raised rib 25 which assists in positioning the end of the wick.

In the illustrative embodiment of the invention, the wick is shown of such a height that the conductor 61 is held well removed from any grounding contact with adjacent metallic parts 55 of the burner. If it is desired to employ wicks of lesser height, or if it is desired to so locate the conductor that it penetrates lower portions of the wick than are shown in Figs. 1 to 5 (as, for example, in Figs. 6 and 7), or if for these or other reasons there arises the possibility of grounding the heating element on the walls of the base, the base may be and preferably is given a superficial insulating coating by enameling the walls thereof in accordance with the disclosure in my prior Patent No. 1,848,206, dated March 8, 1932. Such coating of insulating enamel may be caused to cover the inner and top walls of the fuel groove 31, as indicated by the heavy black lines 82 in Fig. 2 and in greater detail in Fig. 11, so that, even if the resistance heating element 61 should come in contact with the walls thereof, no harm can result.

The described means for starting a combustion tube burner provides for a substantial reduction 75

- in the starting time required,—by starting time referring to the now relatively long interval which must elapse after lighting the wick and before the full fire operation of the burner is reached. When 5 the wick in the now prevailing type of burner is lighted, the flame of the wick is relied upon to initiate combustion and build up the vaporizing capacity of the burner. Such flame however, continues for a substantial interval of time to 10 be relatively feeble and to be limited in respect to intensity of combustion by the relatively small volume of oil vapor volatilized at the edge of the wick and immediately adjacent the zone of combustion.
- 15 In the described starting device, to the amount of oil vapor volatilized by the combustion at and above the edge of the wick is added a substantial and continuing increment of oil vapor vaporized by the heat communicated from the resistance 20 heating element to the oil which is being drawn up into the body of the wick itself.

It follows that not only is the production of oil vapor from the wick itself sharply accelerated but the volume of oil vapor thrown off is materially increased at the critical period of starting, 25 which at present is a long drawn out interval, so that the full fire operation is reached in a substantially shorter time. It is obvious that the thermostatic device may be designed to operate 30 at any desired range of temperature, so that by proper design of the thermostatic cut-out, the heating current through the resistance element, which provides such increased amount of vaporized oil, may be continued until any desired stage 35 in the burner operation has been reached.

The more rapid starting of the burner may be still further promoted by extending the resistance heating element further down into the body of the wick. In Figs. 6 and 7, such an arrangement 40 is shown, the resistance heating element 89 being carried over close to the top edge of the wick, thence angularly down to a point at the side thereof, thence through the wick, and similarly upon the opposite side thereof, and so on throughout the length of the wick.

45 In Figs. 8, 9, and 10 another arrangement is illustrated in which the resistance heating element 91 comprises three longitudinal portions 91^a, 91^b and 91^c. The lower one, 91^a, has one end 50 attached to the connection 77 and extends lengthwise through the lower mid portion of the wick. It then turns reversely on itself and is prolonged to provide the serially connected portion 91^b which 55 extends through the upper mid portion of the wick to a point near the opposite end thereof, where it is then prolonged to provide the reversely extending, serially connected portion 91^c, which interlaces the wick, in the manner shown, closely adjacent the top edge.

60 In this case the portions 91^a and 91^b supplement the oil volatilizing action of the upper portion 91^c. Such resistance heating element or elements, which are supplemental to the upper conductor contiguous to the edge, may be connected either in series, as shown, or in parallel therewith, and may be designed to present a different amount of resistance to the passage of the current to secure differentiated heating effects in the upper and lower portions of the resistor.

70 In the case of the constructions shown in Figs. 6 and 7 and in Figs. 8, 9, and 10, it will be obvious that the wires, beside serving the function of resistors, additionally serve to reinforce the structure of the wick.

75 While I have herein shown and described for

purposes of illustration one specific embodiment of the invention and one particular application thereof, it is to be understood that extensive deviations may be made in the form and relative arrangement of parts and that other uses may be made thereof, all without departing from the spirit of the invention.

I claim:

1. An element for a liquid fuel burner comprising a long, flat, liquid fuel absorbent wick composed of non-conducting fire-resisting material, and a resistance heating element incorporated in said wick and capable, when included in an electric circuit, of being brought to a sufficient temperature to vaporize and ignite the liquid fuel in 10 said wick, said element comprising a conductor threaded lengthwise of the wick, through the insulating material and over the edge thereof to provide a conductive path in which the heating current is localized at or near the wick edge. 15

2. A liquid fuel burner having a base provided with a fuel groove, combustion tube means forming a combustion chamber above said groove, a liquid fuel absorbent wick of electrically non-conducting and fire-resisting material comprising 25 a flat strip set on end in said groove, means for supplying liquid fuel to said groove to saturate said wick, a resistance heating element incorporated in said wick and capable, when included in an electric circuit, of being brought to a sufficient 30 heat to vaporize and ignite the liquid fuel, said element comprising a conductor threaded lengthwise from end to end through the insulating material and over the upper edge of said wick to provide a continuous conductive path in which the 35 heating current is localized at or near the edge of the wick, terminals positioned in but insulated from the base to which the opposite ends of said conductor may be electrically connected, and means for supplying an electric current to said 40 conductor through said terminals.

3. An element for a liquid fuel burner comprising a liquid fuel absorbent wick, a resistance heating element carried by the wick and capable, when included in an electric circuit, of being brought to a sufficient temperature to vaporize and ignite the liquid fuel in said wick, said element comprising a conductor providing a conductive path at or near the edge of the wick, and a supplemental resistance heating element also carried 45 by said wick at a position below the upper edge.

4. An element for a liquid fuel burner comprising a wick, a resistance heating element incorporated in said wick, terminals secured to opposite ends of said heating element, and a protecting 50 sheath covering each end of the wick and holding said terminals in place.

5. A liquid fuel burner having a base provided with walls forming an annular fuel groove, a wick for said groove, a resistance heating element carried by the wick, a terminal positioned in but insulated from the walls of the base, an electric connection secured to the ends of said resistance heating element and adapted to make contact with said base terminal, and means for fixing the 55 end of the wick in said groove and locating it with said connection in definite relation to said base terminal.

6. An element for a liquid fuel burner comprising a liquid fuel absorbent wick composed of fire 70 resisting material, and a resistance heating element incorporated in said wick and capable, when included in an electric circuit, of being brought to a sufficient temperature to vaporize and ignite the liquid fuel in said wick, said element being 75

threaded through said wick and passing alternately to opposite sides thereof.

7. A liquid fuel burner having a base provided with an extended fuel groove, combustion tube means forming a combustion chamber above said groove, a fuel absorbent wick in said groove comprising a substantially flat strip set on edge in said groove and extending throughout the major portion of said groove, means for supplying liquid fuel to said groove to saturate said wick, a resistance heating element incorporated in said wick, extending lengthwise through a major portion of the same and capable, when included in an electric circuit, of being brought to a sufficient heat to vaporize and ignite the liquid fuel, terminals positioned in and insulated from said base in which the opposite ends of said element may be electrically connected, and means for supplying electric current to said element through said terminals.

8. A liquid fuel burner having an elongated fuel groove therein, igniting means for said fuel burner comprising an elongated liquid fuel absorbent wick means extending substantially coextensively with said fuel groove and presenting a portion extending above the liquid level therein, and a vaporizing and igniting element comprising a resistance heating means carried by and contacting said wick throughout the major portion of its length and capable of being connected in an electric circuit, whereby substantially concurrent vaporization and ignition may be effected throughout the major portion of the burner.

9. A liquid fuel burner having a metal base provided with a fuel compartment and means for supplying liquid fuel thereto, combustion tube means forming a combustion chamber above said compartment, a fuel absorbent wicking strip cooperatively positioned in said compartment to facilitate starting, electrical means for igniting said wicking strip including a resistance heating element incorporated therewith and capable, when included in an electric circuit of being brought to a sufficient temperature to vaporize and ignite the liquid fuel in said wicking strip, and an insulating coating over the walls of said compartment which coact with said wicking strip, insuring against short circuiting of the resistance heating element to the metal base.

50 10. A liquid fuel burner of the combustion tube type comprising a base provided with a fuel groove and means for admitting fuel thereto, combustion tube means forming a combustion chamber above said groove, and a starting means in said groove comprising a resistance heating element, an electric circuit for heating said element including a contact member and a thermostatic member adapted to make contact with said contact member and break contact therewith when heated, one of said members being carried by said base and the other by said starting means, thus facilitating placement and removal of said starting means.

11. A liquid fuel burner having a base provided with an elongated fuel groove, means for supplying liquid fuel thereto, combustion tube means forming a combustion chamber above said groove,

a substantially flat strip of wicking removably positioned in said groove in operative relation to and beneath said combustion chamber and presenting a portion extending above the liquid fuel level therein, said wick being composed mainly of fire-resisting, liquid-fuel absorbing, non-conductive material, a vaporizing and heating element carried by the said wicking strip and in heating contact with the material thereof, and establishing a definite current path of approximately fixed resistance therethrough, a current source, connections therefrom to the burner structure, and means embodied in the structure of the burner base and detachably connected with said element to establish an all-metallic current path from said current source and said connections through the said resistance heating element while the wick is in operative position beneath said combustion chamber, and providing for removal of said element with said wicking strip.

12. A liquid fuel burner having a base provided with an elongated fuel groove, means for supplying liquid fuel thereto, combustion tube means forming a combustion chamber above said groove, a substantially flat strip of wicking removably positioned in said groove in operative relation to and beneath said combustion chamber and presenting a portion extending above the liquid fuel level therein, said wick being composed mainly of fire-resisting, liquid-fuel absorbing, non-conductive material, and having incorporated for removal therewith vaporizing and heating means in heating relation with the absorbent material establishing a definite current path of approximately determined resistance through said wicking strip, a current source, connections therefrom to the burner structure, and means embodied in the structure of the burner base detachably connected with said vaporizing and heating means to establish an all-metallic current path from said current source and connections to the said vaporizing and heating means while the wick is in operative position beneath said combustion chamber and providing for removal of said heating means with said wicking strip.

13. A liquid fuel burner of the combustion tube type having a base provided with a fuel groove, combustion tube means forming a combustion chamber above said groove, a fuel absorbent wick in said groove, means for admitting liquid fuel to said groove to saturate said wick, a resistance heating element incorporated in the wick structure for lighting said wick, said wick and resistance heating element being removably mounted as a unit, an electric circuit including said resistance heating element, a thermal cut-out for opening said circuit comprising a fixed contact in said groove but insulated from the walls thereof, and a bi-metallic thermostatic member serially connected to said resistance heating element and carried thereby for removal therewith as a unit, said member normally having contact with said fixed contact and said contacts being out of, but said bi-metallic member extending into, the zone of combustion.

RALLSTON M. SHERMAN.
